UNITED STATES PATENT OFFICE.

JOSEPH F. CHMELIR, OF ST. LOUIS, MISSOURI.

VENTILATING-WINDOW.

SPECIFICATION forming part of Letters Patent No. 683,848, dated October 1, 1901.

Application filed March 18, 1901. Serial No. 51,622. (No model.)

To all whom it may concern:

Be it known that I, JOSEPH F. CHMELIR, a citizen of the United States, residing in the city of St. Louis, in the State of Missouri, have invented certain new and useful Improvements in Ventilating-Windows, of which the following is a full, clear, and exact description, reference being had to the accompanying drawings, forming part of this specification.

My invention relates to that class of windows used in churches and similar large buildings and adapted to be swung into open position to afford ingress and egress of air for proper ventilation. The construction comprises two window-receiving casements centrally hinged in line with each other and so connected as to be capable of swinging in unison and parallel with each other, one of said casements being designed to contain an inner window and the other being designed to contain a storm-window.

My invention consists in features of novelty hereinafter fully described, and pointed out in the claims.

Figure I is a view in elevation of a window constructed according to my invention. Fig. II is a vertical sectional view taken on the line II II, Fig. I. Fig. III is an enlarged detail perspective view of one of the pivot-receiving sockets of the inside-window casement. Fig. IV is an enlarged detail view of the spring-controlled latch by which the window-casements are held closed. Fig. V is an enlarged detail perspective view of fragments of the inner-window casement and the frame in which said casement is mounted and showing one of the hinges on which said casement swings. Fig. VI is a detail perspective view of a fragment of the inner-casement-receiving frame, showing the construction of said frame at the center thereof. Fig. VII is an enlarged horizontal sectional view taken on line VII VII, Fig. II. Fig. VIII is an enlarged detail perspective view of one of the adjustable pivot members to which the outer casement is connected. Fig. IX is an enlarged detail perspective view of one of the controlling-bars connecting the inner and outer casements and by which the pivot member shown in Fig. VIII is carried. Fig. X is an enlarged horizontal sectional view taken

on the line X X, Fig. II. Fig. XI is an enlarged detail cross-sectional view taken through one side of the outer casement and through one of the guards carried thereby.

1 designates a window-casing.

3 designates a frame mounted within the window-casing at the inner side thereof, the said frame being constructed of angle-iron 60 and having flanges 4 thereon, located at the innermost side of the frame at the lower end thereof, and flanges 5, located at the outermost sides of the frame, the said flanges 4 extending upwardly to a position near the vertical center of the window and the flanges 5 extending downwardly to a position also near the vertical center of the window. The ends of the flanges 4 and 5 do not meet each other, there being a space left between them, as seen in Figs. II and VI, within which the casement of the inner window is permitted to swing, as will hereinafter appear.

6 designates an inner casement adapted to receive a window, which may be suitably mounted therein. The casement 6 is preferably constructed of angle-iron, and it is so mounted within the frame 3 that when closed its lower end will rest against the flanges 4 at the lower portion of the frame 3 and its upper end will rest against the flanges 5 at the upper portion of the frame 3. The casement 6 is permitted to swing on a central pivot between the flanges 4 and 5 of the frame 3, it being mounted on pivots 7, carried by brackets 8, fixed to the casement and seated in socket members 9, mounted on the flange 4 of the frame 3. When the casement 6 is in closed position, it is retained firmly within the frame 3 by a latch 10, controlled by a spring 11 and mounted in a housing 13, that is fixed to the casement 6. The latch 10 is provided with a beveled point adapted to engage a hook 14, fixed to the frame 3, and projecting from the latch is an eye 12, adapted to receive a cord, by which the latch may be released from the hook 14 and the casement 6 swung on its pivots into open position.

15 designates an outer casement or storm-window frame, into which a window may be suitably secured. The casement 15 is pivotally supported by a rod 16, that is mounted in sockets 17, carried by brackets 18, that are secured to the window-casing 1.

19 designates guards, preferably of sheet metal, which are riveted or otherwise secured to the lower end of the casement 15 at its edges and arranged to project therefrom across the 5 interstices between the said frame and the window-casing, so as to exclude the passage of currents of air or moisture through said interstices to the interior of the building to which the window is applied. The upper portion 10 of the window-casing is preferably provided at the outside with molding arranged to extend over the edges of the upper end of the outer casement 15, so as to exclude the entrance of air or moisture around said casement. 15

In order to cause the casements 6 and 15 to swing in unison with each other, I connect them at their lower ends by means which will now be described, the said means being provided for adjustment, so as to be adaptable 20 for service upon windows of varying depths.

20 designates pivot-bars pivoted at 21 (see Figs. II and X) to the casement 6, the said bars being provided with longitudinal slots 22.

25 23 designates a pivot-receiving member applied to the pivot-bar 20 and capable of being shifted on said bar according to the requirements necessary to accommodate the application of the parts to window-casements 30 of different depths. The pivot-receiving member 23 is held to the pivot-bar 20 by a set-screw 25, that passes through the slot 22 in said bar and is seated in the member 23, so as to clamp said member in any desired 35 position on the bar 20. The pivot-receiving member 23 is provided with a slot 24, that receives a shifting pivot-bolt 26, which is carried by an arm 27, fixed to the casement 15. The pivot-bolt 26 is adapted to operate 40 through the slot 22 of the pivot-bar 20 and is permitted a limited play only by the limited length of the slot 24. When the casements 6 and 15 are swung on their pivots, the pivot-bar 20, while holding the casements together, 45 permits of their swinging freely; but each time that the casements are closed they return to normal vertical positions in alignment with each other by reason of the link connection effected by the pivot-bars 20 and the

50 pivot-receiving members 23, carried thereby. When the casements 6 and 15 are set in position, the pivot-receiving members 23 are shifted inwardly or outwardly on the bar 20, according to the depth of the window-casing, thereby providing for the proper assemblage 55 of the casements irrespective of the distance they may be placed from each other.

I claim as my invention—

1. In a ventilating-window, the combination of a pair of casements independently 60 mounted at their center on pivot-supports, in substantially the same horizontal plane but in different vertical planes, and means whereby said casements are adjustably connected, substantially as described. 65

2. In a ventilating-window, the combination of a pair of casements pivotally mounted at their center in substantially the same horizontal plane, but in different vertical planes, a pivot-bar connected to the bottom of one 70 of said casements, and means whereby the other casement is adjustably connected to said pivot-bar, substantially as described.

3. In a ventilating-window, the combination of a pair of casements pivotally mounted 75 at their center in substantially the same horizontal plane, but in different vertical planes, a pivot-bar connected to the bottom of one of said casements, a slidable pivot-receiving member adjustably secured to said pivot-bar, 80 and a pivot-bolt carried by said second casement at its bottom arranged to operate in said pivot-receiving member, substantially as described.

4. In a ventilating-window, the combination of a pair of pivotally-mounted casements, a slotted pivot-bar connected to one 85 of said casements, a slotted pivot-receiving member adjustably secured to said pivot-bar, and a pivot-bolt carried by said second casement adapted to operate in the slot in said pivot-receiving member, substantially as described. 90

JOS. F. CHMELIR.

In presence of—

E. S. KNIGHT,
N. V. ALEXANDER.
